UNITED STATES PATENT OFFICE

GERARDUS KAPSENBERG, OF GRONINGEN, NETHERLANDS

CLOSING DEVICE FOR ORGANISM CULTURE VESSELS

Application filed September 26, 1931, Serial No. 565,384, and in the Netherlands September 23, 1930.

In bacteriology tubes, flasks and similar vessels containing a substratum prepared for inoculating with bacteria, moulds or other living organisms, or having been inoculated with said organisms, the separation from the surrounding atmosphere is effected by a plug of wadding. This plug is not an airtight closing but keeps away germs from the air (bacteria, spores of moulds etc.) in a sufficient though not absolute manner.

It may be remarked—and this is important with regard to the hereafter described closing device—that Louis Pasteur kept sterile liquids in flasks in sterile condition by drawing out the neck of said flasks to a capillary tube and bending this capillary tube. Consequently a wadding plug is not inevitably required, but of course it is much easier to apply a wadding plug than to draw out the neck of a tube or flask.

The use of a wadding plug, however, has several drawbacks,

(1) The making of a good wadding plug requires time and skill.

(2) If the culture tube closed by the plug is sterilized in dry condition and the dry sterilizer is heated too high, for instance to 200° C., which may easily occur, the plug becomes brittle and powdery.

(3) In the operation of inoculating and reinoculating this is undesirable because powder of cotton wool falls in the substratum and the closing is effected less easily and is less efficient.

(3) In the filling of the culture tubes with substratum, care must be taken that this does not touch the upper inner side of the tube, because the plug of wadding is applied there and if the substratum is touched by the plug the consequences are:

(a) The wadding plug imbibes some of the material of the substratum so that moulds may easily grow in the plug with the result that infection of the substratum follows soon.

(b) The plug will stick to the tube; it is

difficult to remove; it loses its proper form; and some of the fibres remain sticking to the inner side of the tube, all these causes prevent a sterile inoculation and reinoculation.

(4) In the wet sterilizing method (most generally practised) it occurs that during cooling condensed water reaches the wadding plug, moistens this plug and reaches the substratum which is diluted by it. In a busy trade such a fault is difficult to prevent. Also it may be that the substratum foams and the foam reaches the lower part of the wadding plug. Then again the plug becomes a feeding base for moulds.

(5) When, as usual, a large number of culture tubes, provided with a substratum, are made and kept in store, two difficulties may occur:

(a) The feeding bottom desiccates, by evaporation of water.

(b) In course of time bacteria or moulds grow or fall through the wadding plug.

Concerning desiccation this may be prevented by several artifices, such as providing a layer of paraffin wax or by the use of capsules. These artifices, however, often present difficulties. The growing of bacteria and moulds through the plug is not prevented thereby.

(6) When inoculating and reinoculating, the drawbacks of the wadding plug become evident. The removal of the plug and holding it between the fingers requires some skill. It is inevitable that even skilled persons sometimes let the plug slip out of their hands. In the flashing operation the plug often takes fire. When the cultures are reinoculated the wadding plugs always give some dust, which is especially detrimental when many cultures have to be reinoculated shortly after each other. If the plug sticks to the upper end of the tube (in consequence of the presence of part of the substratum there) reinoculating is difficult. If the inoculations have to be taken many times from the same tube the

plug loses its form, and it becomes more and more difficult to introduce it into the tube. If bacteria grow slowly, such as the tubercle bacillus, desiccation must be prevented. The required artifices are cumbersome and not always sufficient.

(7) The wadding plugs are generally used only once. This is an economical disadvantage.

10 Notwithstanding the drawbacks of the use of a wadding plug, its use is maintained by its real qualities: simplicity, generally sufficient germfree closing, and easy handling.

15 A device combining the qualities of the wadding plug but without its drawbacks is not easily found. Several attempts have been made but were not successful. A device which may be substituted with success for the wadding plug will have to fulfill the following requirements:

- (a) It must fit well to the ordinary culture tubes now generally in use,
- (b) It must fit firmly in these tubes,
- (c) It must not require extra room,
- 25 (d) It must be sterilizable,
- (e) It must not be breakable,
- (f) It must provide a germtight closing,
- (g) It should be as easy to handle as a wadding plug or possibly easier,
- 30 (h) It should not be expensive.

All the substitutes proposed until now for the wadding plug have been unsuccessful. The closing by a reverted glass tube does not come up to the requirements *b, e* and *g*.

35 Such glass caps slip easily from the tubes, are very breakable and not so easy to handle as a wadding plug. A glass cap is also used for closing the special culture tubes, mentioned in the German Patent 454,876. They have the same drawbacks.

40 The cap described in German Patent 508,597 does not come up to the requirements *a, c*, and *g*. This cap fits only specially made tubes or bottles. These must be provided with reversed edges and preferably below with a projecting ring. Between the edge and this ring a ring of asbestos is provided. The cap according to this patent cannot be used in ordinary bacteriologic or microbiologic research.

45 In order to solve the problem of substituting for the ordinary wadding plug a device which completely, and under all conditions of microbiological work, takes its place and at the same time avoids its drawbacks, I have proceeded on the idea that the device should have the same qualities as the wadding plug, but have these qualities in another and better form.

50 The closing cap according to the invention is composed of three parts:

- (1) A rod or handle which may be provided with a knob,
- (2) A bell-shaped cap,
- 55 (3) A little spring inside the cap.

The little rod is a handle and therefore a substitute for the part of the wadding plug extending from the culture tube. It is evident that a rod may be kept much easier and with more certainty between the fingers than a loose mass of cotton wool.

The bell-shaped cap closes germtight. Between the upper edge of the culture tube and the upper edge of the cap, between the outside of the culture tube and the inner side of the cap, between the part projecting from the centre of the cap towards the inner side of the culture tube and said tube, always remains a narrow capillary air space. This is not passed by bacteria because the same conditions prevail here as in the capillary tubes used by Pasteur and as in the spaces between the fibres of a wadding plug. The same causes, which make Pasteur's capillary tube and a wadding plug germtight closings, also prevent bacteria from passing between the cap and the culture tube. It has been shown by experiments that the cap as described is even a better germtight closing than a good wadding plug. Yet there is a sufficient diffusion of air so that bacteria grow very well, at least as well as with the use of a wadding plug. The sterilization takes place without any difficulty because the closing is not hermetic.

The cap does not take more space than an ordinary wadding plug, considering that the projecting part of the wadding plug also projects over the edge of the culture tube.

Resuming the aforesaid it may be said that the cap represents the germtight closing inherent to the wadding plug.

The spring represents the clenching action of the plug. It fixes the cap firmly on the culture tubes without taking outward space. The cap is held more firmly by the spring in the culture tube than the wadding plug is held by its elasticity; one may take up the culture tube by the cap without any inconvenience.

60 The spring is an important part of the cap. It is not so easy to find its correct form. With the spring the cap has become a reliable closing, more reliable than a wadding plug which often gets loose in the culture tube.

The spring is preferably made in such manner that it also enters into the tubes, having an inner diameter somewhat larger or smaller than the mean. The culture tubes most commonly used have an outer diameter very near to 18 mm. The thickness of the glass, however, is more or less variable.

65 For a better understanding of the invention, one construction of the cap according to the invention will now be described with reference to the accompanying drawings.

In these drawings,

Fig. I is a longitudinal section of the cap between the two clips of the spring.

Fig. II is a longitudinal section of the cap at right angles to the section of Fig. I.

Fig. III is a view from below of the position of Fig. I.

Fig. IV is a view through the culture tube with its capsule.

In these figures, the reference characters are applied as follows:—

(a) The knob of the handle,

(b) The rod of the handle,

(c) The bell-shaped cap,

(d) The clenching device by which the spring device is attached to the inner upper side of the cap,

(e) A spring device containing two clips forming one piece,

(f) A circular groove between the disc like member *d* and the side wall of the cap,

(g) A culture tube.

20 The bending of the clips of the spring is such that the width of the curve is greater than the inner diameter of the tube, and if the cap is removed from the tube the spring will generally press against the side wall of the cap.

The mean exterior diameter of the most usual culture tubes is somewhat below 18 mm, and the inner diameter of the closing cap for such culture tubes is about 18½ mm.

30 It must be understood that the details given are intended in no way to limit the invention which may be varied in many ways without departing from the spirit of the invention.

35 The advantages of the described closing device with respect to the wadding plug and other means for closing culture tubes and the like can be explained in the best manner with respect to the requirements given above:

40 (1) A closing by means of a wadding plug or the like, for instance a plug of paperstuff, must be made always anew. This requires much time and some skill. It is often done incorrectly. Closing caps are always ready 45 for use; it requires hardly any time to apply one and this may be done by unskilled persons.

(2) In the preparation of the wadding plugs dust is likely to be formed by which germs of bacteria and moulds may be distributed in the room and may infect substrata. This dust is also disagreeable. The closing caps form no dust.

55 (3) The closing cap is fixed firmly on the culture tube, more firmly than a wadding plug, and of course, much more firmly than a cap without a spring. When removing and storing the tubes the closing caps remain in their place; with wadding plugs this is not always so, and with caps without a spring nearly never occurs.

(4) The culture tube may be lifted up by lifting the closing cap. Generally this is not possible with a wadding plug and also undesirable. This advantage is important if,

as often occurs, a culture tube has to be removed from a tank in which there are many of them. With tubes provided with a closing cap with a handle, this is very simple; it is rather difficult with tubes closed by a wadding plug or a cap without a handle.

(5) A closing cap is not altered by sterilization, even if the temperature in the sterilizer becomes too high. The wadding plug on the contrary is always damaged by sterilization especially if the temperature is too high.

(6) The closing cap may be sterilized separately which is not the case with a wadding plug.

(7) If in the filling operation some material of the substratum has come into contact with the upper inner side of the culture tubes this is practically without any drawback if a closing cap is used. It will not stick to the small surface of contact and there will not be any growth of moulds. Under the same conditions the wadding plug sticks to the tubes and moulds are easily developed.

(8) Foaming of the substratum and flowing in of condensed water are not to be feared if a closing cap is used. The use of closing caps makes it even possible to pile up the usual wire baskets with culture tubes in a wet sterilization process. When wadding plugs are used extra precautions must be taken.

(9) The closing cap prevents to a large extent desiccation of the substratum. Comparative experiments with tubes closed by a normal wadding plug have shown this in a surprising degree.

(10) Complete shutting off from the air for cultivating purposes is effected easily and cleanly by the application of adhesive plaster, a layer of plasticine or the like.

(11) The construction of the closing caps prevents the growing of moulds through the closing; substrata provided with a closing capsule according to the invention remain practically sterile for an indefinite period.

(12) Inoculation and reinoculation are effected much more easily than when using a wadding plug. The handling of the rod and keeping it between the fingers is a very simple manipulation. The troublesome ignition of the wadding plug (and sometimes of all the plugs on a standard) is prevented with the use of closing caps though they are easily sterilized by the application of a flame. The cap retains always its form and therefore can be replaced very easily on the culture tube after inoculation. All this causes the inoculation and reinoculation to be effected much more easily, faster and in a more reliable and pleasant way with the use of a closing cap than with the use of a wadding plug.

(13) The wadding plug is generally used only once. The closing cap may be sterilized many times and always used anew.

(14) The use of a closing cap is much more economical than the use of a wadding plug for the following reasons:

(a) Time and therefore labor are economized because a cap is always ready for use and the inoculation and reinoculation can be effected rapidly.

(b) Substratum is economized because desiccation and infection are avoided.

(c) There is a large economy of cotton wool. Even now it is certain that a cap has more value than 100 wadding plugs, but probably much more. When manufactured to a large scale the cap is a wholesale article.

15 The cap according to the drawings is fit for the most commonly used culture tubes. For culture tubes with a smaller or larger diameter, culture flasks and culture bottles, the dimensions of the cap must be varied accordingly. The construction remains substantially the same.

20 A suitable material for the cap is aluminium, covered with a suitable coating such as bakelite. The springs are preferably made of rust-proof steel, but also other materials may be used.

What I claim is:—

30 1. Closing device for culture vessels, such as culture tubes and flasks for microbiological research work, comprising a bell-shaped cap, and a spring device within said cap for fixing the cap on the vessel.

35 2. Closing device for culture vessels, such as culture tubes and flasks for microbiological research work, comprising a bell-shaped cap having an inner diameter slightly greater than the outer diameter of the part of the vessel on which it is applied, and a spring device within said cap to fix the cap on the vessel.

40 3. Closing device for culture vessels, such as culture tubes and flasks for microbiological research work, comprising a bell-shaped cap having an inner diameter slightly greater than the outer diameter of the part of the vessel on which it is applied, and a spring device within said cap attached to the inner top side of the cap and projecting downwards so as to fix the cap on the vessel.

45 50 4. Closing device according to claim 1, in which the cap is provided with a rod-shaped handle.

55 5. Closing device according to claim 2, in which the cap is provided with a rod-shaped handle.

60 6. Closing device according to claim 3, in which the top of the cap is provided with a rod having a knob.

65 7. Closing device for culture vessels, such as culture tubes and flasks for microbiological research work, comprising a cap having an inner diameter slightly greater than the outer diameter of the mouth of the tube or flask on which it is to be applied, and a spring device within said cap attached to the inner top

side of the cap and extending downwards with two arms, each arm consisting of a curved resilient wire, the width of the curve being somewhat larger than the inner diameter of the tube or flask on which the cap is applied.

70 8. Closing device according to claim 7, having a rod fixed on the top of the cap.

75 9. Closing device for culture vessels, such as culture tubes and flasks for microbiological research work, comprising a cap having an inner diameter slightly greater than the outer diameter of the mouth of the vessel on which it is applied, a spring device within said cap attached to the inner top side of the cap by a disc like member centrally connected with the cap, said spring device consisting of two curved arms of resilient wire extending downwards in the cap, the width of the curve corresponding substantially with the inner diameter of the cap, and a rod-shaped handle fixed on the top of the cap.

80 10. Closing device according to claim 9, in which the rod-shaped handle is provided with a knob.

85 11. Closing device according to claim 9, in which the two arms of the spring are formed of one piece of wire.

In testimony whereof, I affix my signature.

GERARDUS KAPSENBERG.
